UNITED STATES PATENT OFFICE.

FRED H. DANIELS, OF WORCESTER, MASSACHUSETTS.

METHOD OF MAKING BALE-TIES.

SPECIFICATION forming part of Letters Patent No. 703,555, dated July 1, 1902.

Application filed May 13, 1901. Serial No. 60,032. (No model.)

To all whom it may concern:

Be it known that I, FRED H. DANIELS, a citizen of the United States, residing at and whose post-office address is Worcester, in the 5 county of Worcester, State of Massachusetts, have invented certain new and useful Improvements in Methods of Making Bale-Ties; and I do hereby declare the following to be a full, clear, and exact description of the invention, such as will enable others skilled in the 10 art to which it appertains to make and use the same.

The invention pertains to the art of making wire ties for bales of hay, straw, cotton, 15 and the like; and the particular object in view is to economize in the time and labor required in the treatment of the wire between the time it is received from the wire manufacturer until it is discharged in the shape 20 of completed ties from the machines which make the fastenings at the ends; and the invention consists in the method hereinafter described and claimed whereby the several steps of unreeling, annealing, straightening, 25 galvanizing when desired, cutting, and forming the end fastenings are performed continuously and in regular order without any handling of the wires whatever from the time they enter the annealing-furnace, whereby 30 floor-space is economized, the time required in the process is lessened, and the expense and labor incident to the old method are greatly reduced.

The manufacture of wire bale-ties has come 35 to be recognized as an art of itself apart from what is generally known as the "wireworking" art. Large amounts of capital are invested in it, and great numbers of machinists, workmen, and laborers are employed. As 40 now practiced it requires an enormous amount of floor-space in the mill, and a great deal of time and labor is required in the mere handling of the wire and passing it to and fro. The tie manufacturer receives the wire in 45 coils from the draw-benches of the wire-mill. It must first be annealed, and this is always done in the coils, which requires time for cooling after leaving the furnace. It must then be straightened, and special machines 50 are employed for this purpose, these machines operating to uncoil it and take out the kinks and straighten it by stretching it cold. This

part of the process is particularly objectionable for the additional reason to those above stated that the operation of annealing in coils 55 is never as uniform as continuous annealing and for the further reason that straightening by stretching often weakens the wire. After thus straightening the wire it has to be transferred to the cutting-machine for cutting it 60 up into short lengths appropriate for the particular kind of tie desired, and further handling is required to take the cut wires from this machine to the machine or machines for making the end fastenings. Apart from the 65 injurious effect on the ties of this method of annealing and straightening the wire a great deal of time is wasted in transferring it by hand from the machine where one step is performed to that for performing the operation 70 next in order. Moreover, each machine requires one or more workmen to feed and tend it, and additional laborers are required to pass the wire to and fro. My improved method does away with all these objections and apart 75 from the incidental improvement in the quality of the ties permits a greater output with a smaller plant and without any increase in the expense of production, or, to state the same thing in a different way, enables the 80 production of a given output with a smaller original investment for buildings and machinery and with a considerable saving in the current time, labor, and expense of putting the completed ties on the market. 85

The method is as follows, reference being had to the accompanying drawings, illustrating in a diagrammatic way only an apparatus for carrying the same out.

Figure 1 is a plan view, and Fig. 2 a side 90 elevation, of one part of the apparatus, showing the reels for the coils of the wire and the furnace for continuously annealing the same. Fig. 3 is a plan view, and Fig. 4 a side view, of another part of the apparatus, showing the 95 rollers for drawing the wire through the furnace, the machines for cutting the wire into lengths, and one kind of end-fastenings machines. Fig. 5 is a side elevation of the apparatus, showing an arrangement of vats, 100 baths, and tanks employed when it is desired to galvanize the wire. Fig. 6 is a plan view similar to Fig. 3, but showing end-fastenings machines of a different type.

The end-fastenings machines shown in Fig. 3 are employed when ordinary ungalvanized ties for bales of hay, straw, &c., are being made and are of the kind to make fastenings at both ends of the ties, preferably a loop at one end and a cross-head at the other. The corresponding machines of Fig. 6 are such as are usually employed when galvanized ties for cotton-bales are being made and are only intended to make a fastening (usually a twisted loop) at one end; but I wish it understood that so far as the method herein claimed is concerned the kind of end-fastenings machines employed is of no consequence, and I have therefore not attempted to illustrate any particular construction of such machines, but have shown them in a diagrammatic or schematic way only.

Referring now to the drawings, and particularly to the first four figures thereof, A denotes a tubular annealing-furnace of a type too well known to require any description of its construction. Secured on the mill-floor at one end of the furnace is a gang of spindles B, on which the reels of wire C as they come from the draw-benches are supported so as to revolve freely, there being, preferably, a brake of some sort (usually a spring) arranged to act against each reel, so as to keep the wires under tension. The spindles are positioned on the mill-floor in relation to one another and the furnace so that the wires w, leading off to the tubes of the furnace, will not interfere with each other. In Fig. 1 there are twenty-five spindles and reels and the furnace has, preferably, a tube for each wire.

At the end of the furnace whence the wires issue there are a plurality of rollers D, arranged on any convenient supports, and these supports are preferably at the level of the annealing-tubes of the furnace, so as to keep the wires as straight as possible. These rollers should be near enough together to prevent the wires bending injuriously, and they are journaled in their supports, so as to revolve freely as the wires are drawn along them.

Beyond the rollers D and at such distance from the furnace that the wires will be materially cooled in transit is located a large drum E, preferably of wood and advisedly also provided with circumferential grooves, into which the wires from the rollers are received. The wires pass entirely around the drum, and coming up on the rear side lead forward to an arrangement F of drawing-rollers comprising two pairs of small rolls a and b, that are positively driven by a belt-pulley 2 on the shaft of the lower roll of the pair a. The lower rolls of each pair are geared together so as to revolve in the same direction, and each lower roll is geared to the upper one of its pair, so that all four of the rollers are positively driven. The upper rolls are journaled in arms that are provided with adjustable weights, so as to vary the

pressure of the rolls upon the wires, which pass between the upper and lower rolls of the two pairs, and the several rolls are preferably grooved, so that the strands of wire pass between them without interfering with one another. The large drum E is also positively driven, and the motion is conveniently taken from the shaft of the lower roll of the pair a by means of a chain c, the arrangement being such that the peripheral speed of the large drum and that of the drawing-roller is the same, so that there is no stretching of the wires after they leave the drum. The draw-off drum is of so large a diameter that it gives practically no set to the wire as it is drawn around it, and consequently the wire may be said to pass from the furnace to the cutting-machine in a straightened condition.

From the drawing-roll arrangement just described the wires pass to and through cutting-machines G, there being five such machines shown in the drawings and the wires being subdivided into groups and bunches x of five wires each, so that each cutter severs a plurality of wires of the appropriate length for the particular kind of tie desired.

Beyond the cutters are the end-fastening machines H and I, the machines H being located a distance from the cutters just equal to the length of the ties and the machines I being located in any convenient juxtaposition to and beyond the machines first mentioned. Between these machines there runs an apron or belt J, onto which the wires are dropped by the machines H one at a time and by means of which they are delivered onto tables T in such proximity and relation to the machines I as to position them for the latter machines.

The machines H are intended to form loops in the forward ends of the ties, and the wires are passed into the hoppers of these machines in bunches just as they are carried to and through the cutters, though of course the individual wires have to be operated on one at a time by the looping mechanism or mechanisms of the machine, and therefore have to be dropped one at a time from the hoppers into the loopers.

The machines I are intended to form whatever sort of fastenings at the other end of the ties are selected to coöperate with the loops formed by the machines H. Usually these are simple cross-heads; but any other fastening may be employed, and there are many machines known in the art for making them. As the ties are discharged by the machines H they drop onto the traveling carrier J, which advances them and delivers them upon the tables T in the proper position for their rear ends to be received by the machines I, to which they are fed by an attendant in the usual way.

As thus far described the apparatus is adapted only for making the commoner sort of black-wire ties that are used on bales or

bundles of hay, straw, &c. When it is desired to make cotton-ties, which are usually galvanized and are always of better quality than those first mentioned, I introduce between the furnace and the drum of the drawing-roller arrangement any suitable galvanizing apparatus, such as shown in Fig. 5. In this figure 33 are wipers on the edge of stone troughs 4, which contain the acid. 5 denotes a water-trough, through which the wires pass after leaving the acid, and 6 indicates another acid-trough, passage through which completes the cleaning and pickling steps of the galvanizing process. After leaving the last-mentioned trough the wires pass through the zinc-kettle 7, where the molten metal is kept hot over a furnace in the usual manner. The wires are led from this galvanizing apparatus to the drum E, as before described, and thence to the cutting-machines G, beyond which are located the end-fastenings machines H', which are of the same general description as the corresponding machines H of Figs. 3 and 4, though, as illustrated in Fig. 6, a modified form of such machines is shown for the better handling of the galvanized wire, which is considerably larger and stiffer than that out of which the other ties are formed.

Such being the arrangement and operation of the apparatus illustrated in the accompanying drawings, the method of treating and operating on the wire in the manufacture of bale-ties is as follows: It will be understood that the wire is under tension as it passes through the annealing-tubes of the furnace, this tension being due to the weight of the wire itself and the normal resistances encountered in rotating the reels and passing the wire through the furnace as well as to whatever friction-brakes may be employed on the spindles. The wires are pulled through the furnace by the drum and drawing-rollers, and as they pass through the annealing-tubes they are stretched and reduced in diameter and issue therefrom at a red heat, which, however, rapidly cools off as the wires pass over the rollers D on their way to the drum E. As before intimated, this drum is located so far from the furnace that the wire, which it will be understood passes along very slowly, has ample time to set and cool before passing around the drum. The rollers D are necessary to support the wire between the furnace and the drum, for the reason that the wire is at that time too soft to support itself. The wire as it passes around the drum D gets very taut, and all kinks and crooks are then eliminated before it reaches the rolls a b, whence it issues perfectly straight and ready to be cut into lengths without further treatment. The location of the cutters G, so far as distance from the rolls is concerned, is a matter of no particular importance, and they may be located as the available floor-space may require or permit.

As before stated, the wires are separated into bundles and groups after leaving the

drawing-rollers, so that each cutter severs a number of wires at each stroke. In Figs. 3 and 4 there are five cutters shown, and of course five machines for making the end fastenings are employed with this arrangement. Any number of cutters, however, may be used, and in Fig. 6 six are shown, together with the same number of end-fastenings machines.

75

From the drawing-rolls the wires pass clear through the cutters until their front ends bring up in the machines H, when the cutters are actuated and the strands are cut the proper length and left with their front ends in the receivers or hoppers of said machines, where they accumulate and, as in all machines of the sort, are dropped one at a time into the looping, twisting, or whatever other mechanism is employed to form the end fastenings. As fast as these fastenings are made the ties are discharged onto the continuously-moving apron or belt J, whence they are carried to and pass the machines I, so that said machines may operate on their rear ends. The aprons are so arranged with relation to the tables T and these latter are so located relatively to the machines I that when the ties are discharged by the aprons they are deposited on the tables in position to have their rear ends received into the hoppers of these machines without further movement or handling.

As already explained, the invention is not limited to the employment of any particular machines for making the end fastenings on the ties. I prefer, however, to employ the machines heretofore patented to me and Clinton S. Marshall jointly on the 3d day of July, 1900, Nos. 652,953 and 652,998, and the machine H of the third and fourth figures may be understood to be the machine of Patent No. 652,953, and the machine H' of Fig. 6 may likewise be understood to be the machine of Patent No. 652,998. Any sort of an end-fastenings machine may be used at the point I.

Having thus described my invention, what I claim, and desire to secure by Letters Patent, is—

1. In the art of making wire ties for bales of hay, cotton, and the like, the herein-described improvement consisting in continuously passing the wire through an annealing-furnace as it is unwound from the coils, drawing it under tension through said furnace so as to stretch and straighten it while hot, maintaining it in straightened condition and allowing it to set and cool in transit thence to a cutting-machine, cutting it into lengths appropriate to the particular kind of tie required, and delivering it without handling to the end-fastenings machine.

2. In the art of making wire ties for bales of hay, cotton, and the like, the herein-described improvement consisting in continuously passing a series of wires concurrently and simultaneously through an annealing-furnace as they are unwound from their coils, drawing the wires under tension through said

As before stated, the wires are separated into bundles and groups after leaving the

furnace so as to stretch and straighten them while hot, maintaining them in straightened condition and allowing them to set and cool in transit thence to a cutting-machine, simultaneously cutting a plurality of the wires into a bunch or bunches of the appropriate length for the particular kind of tie required, delivering the bunch or bunches to a machine or machines for forming the end fastenings, and forming said fastenings on the ties one at a time.

3. In the art of making wire ties for bales of hay, cotton, and the like, the herein-described improvement consisting in simultaneously and continuously passing a series of wires through an annealing-furnace as they are unwound from their coils, drawing the wires under tension through said furnace so as to stretch and straighten them while hot, maintaining said wires in straightened condition and allowing them to set and cool in transit, dividing the series into bunches and conducting each bunch to a separate cutting-machine, simultaneously cutting the wires of each bunch into lengths appropriate to the particular kind of tie required, and delivering said bunches without handling to separate end-fastenings machines.

4. In the art of making wire ties for bales of hay, cotton, and the like, the herein-described improvement consisting in continuously passing the wire through an annealing-furnace, drawing it under tension through

said furnace so as to stretch and straighten it while hot, galvanizing the wire while passing between the furnace and the drawing apparatus, allowing it to set and cool in transit thence to a cutting-machine, cutting it into lengths appropriate to the particular kind of tie required, and delivering it without handling to the end-fastenings machine.

5. In the art of making wire ties for bales of hay, cotton, and the like, the herein-described improvement consisting in continuously passing the wire through an annealing-furnace as it is unwound from the coils, drawing it under tension through said furnace so as to stretch and straighten it while hot, maintaining it in straightened condition and allowing it to set and cool in transit thence to a machine for making a fastening on the front end, cutting the wire at a point sufficiently removed from the machine to make ties of the desired length, passing the cut lengths end-wise from said machine to and past another end-fastenings machine, and forming a fastening on the rear end of the wire to coöperate with the one previously formed on the front end.

In testimony whereof I affix my signature in presence of two witnesses.

FRED H. DANIELS.
